UNITED STATES PATENT OFFICE

OTTO STRUFE, OF DWIGHT, ILLINOIS

REFRIGERATOR

Application filed September 7, 1929. Serial No. 390,909.

These improvements relate to refrigerators, with special reference to ice compartment construction and devices therefor.

Heretofore it has been the custom to insert in the icing compartment of refrigerators a substantially large cake of ice, say fifty pounds, one hundred pounds or two hundred pounds in weight according to the size of the refrigerator, and to pile on top of the fresh cake and also around its sides the smaller pieces which usually result from breaking up with a pick the piece or pieces remaining in the chamber or produced at the refilling. The iceman usually puts the remaining piece on the floor to break it up and then packs the smaller pieces into the refrigerator.

It is the custom of housewives to pack milk and beverage bottles, fruit, vegetables and dishes containing food around and on top of the ice in the refrigerator, from which practice many mishaps occur through the falling down of ice pieces piled on top of the main piece, and also when it is attempted to break up some of these smaller pieces with the pick for immediate use outside the refrigerator.

The present improvements avoid objections of the kind referred to, provide for a greater capacity of the refrigerator for storing ice, render the smaller pieces of ice more readily available, provide more advantageous places for food articles closely adjacent to ice and in a generally highly refrigerated area and without the danger of spillage, breakage, etc. heretofore commonly experienced, and, in general, improve the sanitary conditions, simplify operations, increase the efficiency of the device, and promote convenience in use.

In the drawing Figure 1 is a fragmentary face and partly sectional view showing a refrigerator construction in accordance with this invention; Fig. 2 is a side elevation of the parts shown in Fig. 1, as on the broken section line 2—2 thereof; Fig. 3 is a perspective of a basket-like container or receptacle shown in Figs. 1 and 2; and Fig. 4 is a perspective of the ice-holding platform or partition between the upper and lower ice chambers of Figs. 1 and 2.

The refrigerator in general may be constructed according to well-known practices,

and these improvements may be variously embodied in the different types of refrigerators to which applicable.

I provide walls forming an upper ice compartment A, a lower ice compartment B, and, 55 where the basket-like container of Fig. 3 is employed, an ice compartment C. When the basket-like device is used the compartment B will ordinarily not be used for holding ice, although the several constructions may be so 60 proportioned as to adapt it for holding other articles.

The walls defining compartments A and B are a top wall 10, a front wall largely consisting of the door 11, a rear wall 12 and side walls 13 and 14, the wall 14 preferably terminating short of the top wall 10 to provide an open space for the free flow of ventilating air and having ventilation openings as 15 therein placing compartment B in communication 70 with some other compartment.

In the preferred construction there is a plate-like, readily removable platform 20 resting on channel iron cleats 21 and which divides compartment A from compartment B, 75 and compartment B has a sheet metal bottom wall 22 provided with a drain opening 18.

An advantageous form of the platform 20 is shown in Fig. 4 as comprising a plurality of longitudinally extending metallic pieces 23 in parallel arrangement and held in spaced apart relation by transverse pieces 24, 25 and 26. The only feature of novelty in connection with the platform 20 as illustrated is the provision of a substantially large opening 27 80 therein which is produced by using a relatively short platform piece 28 between the cross-pieces 25 and 26. The opening 27 is large enough to pass the smaller pieces of ice out of compartment A into a lower compartment. 85

Assuming the device of Fig. 3 to be omitted from Figs. 1 and 2, compartment B becomes a chamber suitable for holding the smaller pieces of ice. A removable plate at 29 (Fig. 2) may be employed to give greater effective 90 depth to the compartment in front. Assume the iceman about to refill compartment A with a cake of ice which ought to occupy substantially its entire capacity. He finds remnants of a former filling in compartment A 95 100

and proceeds to break them up with his pick into smaller pieces and to pass them through the opening 27 of platform 20. Compartment A becomes entirely cleared to receive the new 5 cake and the smaller pieces are not only in an out-of-the-way place but they remain in the vicinity of the larger piece and receive protecting refrigeration from it, extending their life, while remaining in the refrigerating part 10 of the device and continuing to supply refrigerated air to adjacent compartments containing food.

It often happens that the iceman is able to 15 deliver a quantity of ice in small pieces, and sometimes it is ordered in small pieces. In such case the lower compartment B can be substantially filled with that form while a larger piece occupies compartment A.

Small pieces of ice are frequently desired 20 outside the refrigerator and these can be obtained very readily from compartment B. The practice has come into vogue of supplying to the home ice in cubes. A quantity of such cubes could quite conveniently and satisfactorily be carried in compartment B.

The bars 23 are shown as being so arranged 25 that if space exists at the sides of the cake in compartment A articles may be placed beside the ice in that chamber, and without danger from falling pieces.

Compartment B is adapted also for the accommodation of bottles, vegetables, etc., and where the smaller pieces of ice do not occupy 30 too much of its space, this compartment is peculiarly advantageous for articles calling for a relatively high degree of refrigeration. The construction is peculiarly advantageous, 35 therefore, apart from the benefits arising from its use as a storage compartment for ice pieces. Of course at the time of a refilling 40 operation if compartment B were occupied by bottles, dishes, etc. the iceman would be expected to transfer the smaller pieces by hand to the lower compartment; but the food 45 articles would ordinarily be first removed.

The construction is peculiarly advantageous in connection with what is known as outside icing, now rapidly coming into more 50 general practice. In such case, as is well known, the rear wall 12 is provided with a doorway through which the ice is inserted. In such instance the iceman does not enter the house, or, if it be a rear-door refrigerator serviced within the house, the front door as 55 still remains closed. In such case the iceman breaks up the smaller pieces in compartment A and pushes them into the opening 27 of the platform.

The receptacle of Fig. 3 will ordinarily be 60 of sheet metal and comprises a bottom wall 30, upstanding side walls 31, an upstanding rear wall 32, a partial front wall 33 and preferably a removable front wall piece 34, the latter resting in supports 35 secured to the 65 side walls respectively. The side walls are

flanged outwardly at 36 and these flanges are adapted to rest on the lower web 21a of the channel iron piece 21 to such effect that the basket as a whole may readily be inserted in and withdrawn from compartment B. The 70 upstanding walls of the container or receptacle are ventilated, preferably by forming inwardly-and-downwardly inclined leaves 38 from the metal walls, thus leaving openings which are effectively covered to prevent the 75 smaller pieces of ice from falling through. The bottom 30 preferably has a drain opening 30a.

Among the advantages of such a removable container are that it may be lifted away 80 bodily for application or removal of articles or objects and for cleaning. The baffle 34 illustrates one form of removable closure for the front end. This plate 34 may be lifted away for easy access to the hollow interior 85 without removing the device as a whole, although the basket-like receptacle may be withdrawn partially from time to time for such access.

I contemplate as being included in these 90 improvements all such variations, departures and modifications from what is thus specifically illustrated and described as fall within the scope of the appended claims.

I claim:

1. In a refrigerator the combination of 100 walls forming two chambers, one thereof being an upper chamber for a substantially large cake of ice, the other being a lower chamber adapted to accommodate smaller pieces of ice, articles of food, etc., one of the defining walls being a substantially horizontally disposed platform having openings therethrough and positioned between the two chambers, an open-top receptacle adapted to hold small pieces of ice, and means for supporting the receptacle in the lower chamber below said platform.

2. The combination of claim 1 hereof in 105 which said supporting means are adapted to provide for the ready removability of the receptacle.

3. A readily removable receptacle for 110 small pieces of ice in a refrigerator comprising in combination a bottom wall, and walls upstanding from the bottom wall forming a basket-like device sufficiently open at the top to admit the passage of small pieces of ice downward into the receptacle, upstanding 115 walls having ventilation openings therein, with means adapted to coact with supporting means in the refrigerator for holding the receptacle in the refrigerator for ready removability.

4. The device of claim 3 hereof in which 120 the normally front wall of the device has movable closure means.

5. The device of claim 3 hereof in which 125 the ventilation openings of upstanding walls are associated with inwardly-projecting and

downwardly inclined protective covering elements.

6. In a refrigerator the combination of walls defining two substantially large chambers, one directly above the other one for a substantially large cake of ice and the other for smaller pieces of ice, food articles, etc., one of the defining walls being common to both chambers and having a sufficiently large opening therethrough to pass such smaller pieces.

7. In a refrigerator the combination of walls defining two chambers, one thereof being an upper chamber for a substantially large cake of ice and the other being a substantially large lower chamber for smaller pieces of ice, articles of food, etc., one of the defining walls being a substantially horizontally disposed partition common to both chambers and having a sufficiently large opening therethrough to pass such smaller pieces.
